ELECTRIC PICTURE TRANSMISSION

Filed March 29, 1928

BY

INVENTOR
Wilhelm Scheppmann
Otto Rathy
ATTORNEY

UNITED STATES PATENT OFFICE.

WILHELM SCHEPPMANN, OF BERLIN-TEMPELHOF, GERMANY.

ELECTRIC PICTURE TRANSMISSION.

Application filed March 29, 1928, Serial No. 265,779, and in Germany April 5, 1927.

The present invention relates to electric picture transmission systems, e. g., those working according to the telegraphic, or an equivalent principle.

5 The object of this invention is particularly directed to an improved and simple means for reproducing the picture, drawing, or document at the receiving station.

Another object of the present invention is 10 to provide a reproduction means which is very simple and does not need further treatment after the picture has been received.

Still another object of the present invention is to provide a simple means for receiving 15 pictures, drawings, and documents sent out by broadcasting stations for amateurs.

My invention is more particularly described in the following disclosure taken with reference to the appended drawing, which 20 shows schematically an apparatus in the simplest form embodying the present invention, of which

Fig. 1 shows a side elevation, and

Fig. 2 shows a front view of a receiving apparatus in its simplest form.

The reproduction of pictures at a receiving station, even in a rough manner, has always been connected with trouble and inconvenience. Well-known methods are those working 30 mechanically whereby the individual picture elements are printed by a printing mechanism magnetically operated by the picture signals. Another method of copying is that using a photographic registering paper.

35 Still another method which has become known, uses the chemical action on the registering paper. This latter method, too, presents practical inconveniences in that the paper has to undergo subsequent chemical treatment.

According to my invention, I use as registration means a sheet of paper or similar material covered with a thin layer of wax or equivalent material of a color different from 45 that of said paper. In a preferred embodiment the paper is of a darker color than the applied layer of wax. Only a small pressure on the layer exercised by a sharp tool operated by the picture current impulses will 50 suffice to remove or scratch off the layer so that the paper will be laid open. Experiments have shown that by this method lines as thin as a hair may be produced in the wax layer. This latter may be made so thin 55 (about 1/100 to 2/100 cm), that a very slight pressure produced by a stylus operated by an

armature or a membrane will produce a mark on the layer. The armature or membrane is actuated by the picture current impulses received from the transmitting station. In the 60 well-known telegraphic system these current impulses are of shorter or longer duration, and will produce corresponding shorter or longer scratchings on the receiving paper, and thus build up the picture.

65 In the drawings a preferred embodiment of my invention is represented in a schematic manner which is well adapted for the use in picture broadcasting on account of its simplicity.

70 Similar reference numbers refer to similar elements. Numeral 1 is a rotating cylinder moved at the same time lengthwise in the direction of its axis. This cylinder is operated synchronously with a similar cylinder arranged at the transmitting station intended for scanning the picture to be transmitted. This latter may be prepared by applying a 75 non-conducting material to a conducting sheet to be mounted on the transmitting cylinder. A stylus or feeler scanning the picture on the transmitting station in a spiral-like manner opens and closes an electric circuit and sends corresponding current impulses to the receiving station. This transmission may be effected by means of wire or 80 by wireless, as is well-known in the art. These current impulses energize a receiving magnet 4. The magnet 4 operates a lever 5 at the other end of which a stylus 6 is attached. A spring 7 is provided to hold the lever in its zero position, i. e., the position at the time when coil 4 is not energized. The registration paper 2 bearing the thin layer 85 of wax 3 is fixed on the receiving cylinder 1. Each time a picture current impulse arrives 90 from the sending station the stylus 6 is pressed against the paper 2, scratching off the wax layer on that particular spot. Thus, the 95 whole picture, drawing, or document is gradually reconstructed.

100 The system described is very well adapted for transmitting so-called black and white pictures such as drawings, written or printed documents, weather maps, and is especially 105 useful in wireless transmission for broadcasting purposes on account of its simplicity and easy operation. An inclined straight line transmitted from the sending station would look on the receiving sheet somewhat as 110 shown at L in Fig. 2.

The operation of the device represented in

the drawing may also be such that normally the stylus 6 is pressing on the registration paper, and that an incoming picture current impulse will remove it therefrom. Thus, a negative picture with respect to that obtained before, will be received.

The synchronization of the sending and receiving cylinders may be effected in any known manner which is not described here, 10 as being out of the scope of this invention.

Having described my invention, what I believe to be new and desire to secure and protect by Letters Patent of the United States is:—

15 1. Means for picture reproduction in electric picture transmission systems, comprising a sheet of registration material having a dark colored background, a layer of wax of light color compared to said sheet applied to said sheet, and means to remove said layer in accordance with the picture current impulses whereby a positive picture is produced.

20 2. Means for picture reproduction in electric picture transmission systems, comprising a sheet of registration paper having a dark shade background, a layer of wax having a lighter color applied uniformly to said

paper, and means operated in accordance with the picture current impulses to scratch off said layer to directly produce a positive.

30

3. Means for reproduction of visual images by electric impulses comprising a cylinder, a registration surface on said cylinder having a dark colored background, a layer of wax of light color compared to said surface on said surface, and means for recording the image elements corresponding to said electric impulses by mechanical indentations on said wax layer whereby a positive picture is produced.

35

4. Means for reproduction of visual images by electric impulses comprising a cylinder, a registration surface on said cylinder having a dark shade background, a layer of wax of light color compared to said surface on said surface, and means comprising an electrically operated stylus for producing mechanical indentations of said wax layer in accordance to said image elements whereby a positive picture is produced.

40

50 In testimony whereof I have affixed my signature.

WILHELM SCHEPPMANN.
